HYDRAULIC SERVOMOTOR SYSTEM

Peter G. Ipsen, Schenectady, N. Y., assignor to General Electric Company, a corporation of New York

Application April 27, 1955, Serial No. 504,211

5 Claims. (Cl. 137—34)

This invention relates to a system for controlling the supply of motive fluid to a turbomachine, particularly to a hydraulic servomotor system which is regulated by oil pressure to actuate the main control valves of a steam turbine.

In the operation of a steam turbine it is desired to have quick opening and closing times of the main control valves. The conventional way of regulating the main valves of a steam turbine is by a separate oil pressure system which actuates a double-acting servomotor connected to the main valves to move them to open or closed position. The oil pressure system may include a centrifugal pump which is operated by the main shaft of the steam turbine. The centrifugal pump supplies oil to the servomotor in accordance with the setting of an intermediate pilot valve which is controlled by a conventional governor.

With present designs, a "skirted" piston is used to obtain fast closing without requiring such a high rate of oil flow as would be required if a skirt was not used. This arrangement is satisfactory since the force required to close the main valves is small relative to that required to open them, and furthermore, it is feasible to have a valve opening time which is appreciably slower than the closing time.

The use of a skirt, however, introduces a problem in upsetting the balance in the oil flows in the hydraulic system. This results from the fact that when the servomotor is moved in a direction to open the main valves the flow out of the main servomotor is about one-half that flowing in and the pump inlet pressure falls off considerably. Using a "skirted" piston brings about an opening time on the order of 3 seconds as contrasted with a closing time on the order of one-half second. This arrangement is quite satisfactory on units which utilize only one main servomotor since reasonable opening times can be obtained without serious decrease in the pressure at the inlet side of the centrifugal pump. However, when it is desired to utilize several large servomotors there arises the possible danger that it may be difficult to get reasonable valve opening times without having the pump inlet pressure drop to zero. An instance of this is that in a certain new "double automatic extraction turbine" three large servomotors are used, all supplied with operating liquid from the same pump.

Accordingly, it is an object of this invention to provide an improved hydraulic system which actuates a valve for controlling the flow of motive fluid to a turbine, with desired opening and closing times.

A further object is to provide an improved hydraulic servomotor mechanism having a "differential displacement" which provides for different valve opening and closing times, but which maintains a reasonable valve opening time by alternately storing up and supplying oil to the inlet of the pump supplying operating fluid to the servomotor, so that regardless of the number of servomotors supplied by the pump, the pump inlet pressure will not be seriously reduced.

2

Other objects and advantages will be apparent from the following description taken in connection with the accompanying drawing, which diagrammatically illustrates a hydraulic servomotor incorporating the invention and arranged to operate the main control valves of a steam turbine.

Generally stated, the invention is practiced by providing variable volume reservoir means associated with the main servomotor. The reservoir draws in a portion of the oil discharged from the main servomotor during closing movement of the main valve and returns the stored oil to the inlet side of the pump during valve opening movement, to supplement the oil discharged from the main servomotor so as to prevent the amount of oil available at the inlet side of the pump from being reduced to a quantity providing undesirable inlet pressures at the centrifugal pump, for either opening or closing movements of the main valve.

Referring now to the drawing, the invention is disclosed as applied to a steam turbine 1 having a main shaft 2 which drives a centrifugal pump 3. The centrifugal pump 3 supplies oil under pressure to a servomechanism 11 which controls the opening and closing of the main steam valve 1a through a lever mechanism 16, 17 which rotates about pivot 15.

The centrifugal pump 3 is not self-priming and receives oil through inlet conduit 7 from a pump priming system, described more particularly in the U. S. Patent 2,440,980 issued May 4, 1948, on an application of R. Sheppard and assigned to the same assignee as the present invention.

Briefly, the pump priming system comprises a starting motor 20 which drives an auxiliary centrifugal pump 21. The pump 21 is located in a sump 26 and supplies oil through a conduit 23 and check valve 22 to provide the required oil for operation of the hydraulic servomotor mechanism when the turbine is at a standstill or at such a low speed that main pump 3 cannot supply the necessary oil. The oil, under pressure, supplied by pump 21 acts on turbine 24 to drive the booster pump 25 which establishes a pressure at the inlet of the main pump 3 through conduit 7. Check valves 4 and 6 prevent oil pumped by the auxiliary pump 21 from flowing back to the oil tank 26 through conduit 7.

The hydraulic servomotor 11 is initially actuated by providing oil from pump 21 to the servomotor through conduits 23, 13, 5, pilot valve 8 and line 10. This is permitted by the action of governor 8b. When the turbine is shut down, the governor 8b collapses with the result that valve stem 8f is moved up to uncover conduit port 10a so as to receive oil from line 5 when starting motor 20 is energized. After the turbine is running at rated speed the main pump 3 takes over, forcing check valve 22 closed and the auxiliary pump 21 may be shut down. This starting operation is noted merely to give a more complete picture of the system, but is not essential to an understanding of the present invention.

The centrifugal pump 3 provides oil under pressure to the main hydraulic servomotor 11 through conduit 5, check valve 4, pilot valve 8, and conduits 9 or 10 depending on whether the main servomotor is to be actuated in a direction to move the valve 1a to open or closed position.

To control the flow of oil between conduits 5 and conduits 9 or 10, a pilot valve 8 is used. The pilot valve 8 is a conventional piston valve having a series of openings adapted to receive conduits 5, 9, 10, 14a, and 14b. Within the pilot valve 8 is a double piston arrangement 8d, 8e which pistons are axially disposed on rod 8f. The pistons 8d, 8e are located to control the flow of oil at ports 9a, 10a respectively. When rod 8f is moved downwardly, conduit 5 is connected with line 9 and conduit 10 with

line 14b. In this position, the oil from centrifugal pump 3 acts on the servomotor 11 to move the main valves to a closed position. At the same time the conduits 10 and 14b are interconnected to vent the oil discharged from the servomotor 11 back to the inlet of centrifugal pump 3. If the pilot valve 8 is moved in the upward direction the conduits 5, 10 would be interconnected to supply oil to the servomotor to move it in the direction to open the valves 1a. The oil discharged from the servomotor would then be discharged through lines 9, 14a back to the inlet of centrifugal pump 3.

The pilot valve is regulated in the conventional manner by a governor 8b which operates in accordance with the speed of the main turbine shaft 2 through gears 8a. This method of operation is conventional and is cited by way of example only.

The main servomotor 11 comprises a housing 11g containing therein a "skirted" piston 11b. Piston 11b divides the housing 11g into chambers 11a, 11c. Extending from the opposite sides of the piston 11b are rods 11h, 11i. The diameters of the piston rods 11h, 11i are very substantially different, so the effective area of piston 11b subject to the oil pressure in chamber 11a is substantially one-half the effective area of piston 11b which is subject to the pressure in chamber 11c. This ratio between the effective areas on the opposite sides of piston 11b is by way of example only, since it will be understood by those skilled in the art that this ratio can be varied as selected by the designers to secure a desired relation between the times required for opening and closing the valve 1a.

In accordance with the invention, the main servomotor defines a supplementary casing 11d adjacent the bottom portion of casing 11g. The small diameter rod 11i extends through the bottom of casing 11g and top of casing 11d. The chamber 11f is formed between the casing 11d and piston 11e secured to the rod 11i. The effective area of piston 11e is equal to the difference between the effective lower and upper areas of piston 11b. Thus the sum of the upper effective area of pistons 11b and 11e (in chambers 11a, 11f) is equal to the lower effective area of piston 11b (in chamber 11c).

The chamber 11f is connected with the inlet 7 of centrifugal pump 3 through conduit 14c. Conduit 14c is also connected to conduits 14a and 14b for reasons to be described later.

The function of hydraulic servomotor 11 is to move main valve 1a to a closed or open position in response to the oil pressure in the chambers 11a and 11c respectively.

The operation of the hydraulic servomotor system is as follows.

The starting motor 20 is energized to operate the centrifugal pump 21 disposed in the oil sump 26. Oil pressure is thus supplied through check valve 22, conduits 23, 13, and 5, pilot valve 8, conduit 10 and into chamber 11c. This takes place when the governor 8b is collapsed to uncover port 10a. The oil pressure in chamber 11c moves piston 11b in the upward direction to open valve 1a to admit steam to the turbine 1. The pump 21 also provides oil pressure through conduit 23 to drive the hydraulic turbine rotor 24. The turbine rotor in turn drives the priming pump 25 which supplies oil under pressure to the inlet of pump 3 through conduit 7.

When the turbine 1 is started, it drives the centrifugal pump 3 through the drive shaft 2. Part of the output of the pump flows through conduits 13 and 23 to drive the turbine 24. When this happens, the starting motor 20 is shut off.

The governor 8b is controlled by the speed of shaft 2 to regulate the pilot valve 8 which controls the oil flowing from conduit 5 to either conduits 9 or 10. The speed of the shaft 2 is controlled in accordance with the operating requirements of the turbine.

When, in response to an operating condition of the turbine, less steam is required the following takes place:

The governor 8b, in response to the increased speed of shaft 2, actuates the pilot valve 8 in the downward direction. This downward movement of the pilot valve 8 interconnects the conduits 5 with 9 and 10 with 14b. The oil discharged by the centrifugal pump 3 then flows through check valve 4, conduit 5, pilot valve 8, conduit 9 and finally into servomotor chamber 11a where it acts on piston 11b to move it in a downward direction. This downward motion of piston 11b acts through linkage 16, 17, which pivot about fulcrum 15 to move valve 1a in the closing direction. Due to the ratio between the effective areas on the opposite sides of piston 11b, the downward movement of the piston 11b displaces twice the amount of oil from chamber 11c than is received in chamber 11a. This oil discharged from chamber 11c flows through conduit 10, pilot valve 8 and into conduit 14b.

The downward movement of piston 11b also caused piston 11e to enlarge the size of chamber 11f. This draws oil from conduit 14b through conduit 14c into chamber 11f. Since the effective area of piston 11e is equal to the difference between the effective areas on the opposite sides of piston 11b, the chamber 11f will be enlarged that amount necessary to store the difference between the oil displaced from the chamber 11c and that flowing into chamber 11a. The balance will flow through conduits 14 and 7 to the inlet side of pump 3.

When the pilot valve 8 is moved in an upward direction the following takes place. The oil is pumped from centrifugal pump 3 through conduit 5, pilot valve 8, conduit 10 and into the chamber 11c. This buildup of pressure in chamber 11c tends to move piston 11b in an upward direction to move the valve 1a in the opening direction. The oil in chamber 11a is forced out into conduit 9 and flows through pilot valve 8 into conduit 14a. Since the amount of oil flowing out of chamber 11a is substantially equal to one-half that flowing into chamber 11c (due to the difference between the effective areas defined by the respective sides of piston 11b) it can be seen that the amount of oil available at the inlet side of centrifugal pump 3 would be diminished by the difference between the oil flowing in conduits 9 and 10 unless a supplementary source of oil is provided. Any such reduction in the amount of oil available would reduce the inlet pressure available to pump 3. If there were a number of servomotors all being supplied by the same pump, the inlet pressure could drop to zero, which would, of course, seriously affect the operation of the centrifugal type pump.

This supplementary source of oil is provided by the reservoir 11f attached to the main servomotor. When the piston 11b moves in an upward direction it carries along with it through rod 11i the piston 11e. The piston 11e discharges the stored up oil in chamber 11f into conduit 14c. The size of the piston 11e is such that the amount of oil discharged to conduit 14c is equal to the difference between the oil flowing into and out of servomotor 11. Thus, the amount of oil flowing to the inlet side of centrifugal pump 3 is substantially equal to the amount of oil pumped through conduit 5 to the chamber 11c. The inlet pressure of the centrifugal pump is thereby maintained substantially constant.

Thus it can be seen that with the aid of this invention, the quantity of oil available at the inlet side of the main pump 3 is maintained substantially constant regardless of the number of servomotors supplied by the centrifugal pump 3. This prevents the inlet pressure of centrifugal pump 3 from dropping off substantially.

While a single embodiment of the invention has been described in detail herein, it will be obvious to those skilled in the art that many changes and substitutions of equivalents might be made. For example, it may be desirable to make the upper area of piston 11e somewhat less than the difference between the upper and lower areas of piston 11b. This can be done to achieve a better balance regarding the drop in main pump inlet pressure during opening and closing strokes of the servomotor.

This drop in pressure will occur because the extra flow delivered by main pump 3 during motion of the servomotor can be obtained only at somewhat reduced hydraulic pressure, due to the centrifugal pump's flow characteristics. This reduces the available energy to the oil turbine 24; pump 25 will slow down; and the pressure in conduit 7 will tend to drop. This action can be counteracted to any desired extent for opening or closing stroke (not both) by returning more oil to the main pump inlet than is taken from it by the servomotor 11. Since the maintenance of very rapid closing time is of prime importance, this can be done by reducing the displacement of piston 11e. Doing this, however, will increase the minimum possible opening time because on opening there will be less oil returned to the main pump than is taken from it. Considerable latitude exists for moving in this direction, because opening time can be perhaps anywhere from 6 to 10 times the closing time.

It is, of course, desired to cover by the appended claims all such modifications as fall within the true spirit and scope of the invention.

What I claim as new and desire to secure by Letters Patent of the United States is:

1. A hydraulic system comprising a servomotor, a pump for supplying operating fluid under pressure to the servomotor, a pilot valve for controlling the flow between the pump and the servomotor, the servomotor comprising a first housing, a first piston means defining two different effective areas with said first housing, a first chamber defined between the first housing and the larger of the two areas, a second chamber defined between the first housing and the smaller of the two areas, a second housing defining therein a third chamber between the second housing and a second piston located in said second housing, means connecting the second piston to said first piston whereby when the first piston is moved in a direction to decrease the size of the first chamber the second and third chambers are increased in size, and conduit means interconnecting the pump, pilot valve, and said first and second housings whereby, upon movement of the pilot valve to direct the flow of fluid from the pump to the second chamber, the first piston will move in a direction tending to displace fluid from the first chamber to the inlet of the pump, the second piston will move to enlarge the third chamber into which fluid not recirculated by the pump is directed and stored, and, upon movement of the pilot valve in the opposite direction, fluid is supplied to the first chamber and the first piston displaces fluid from the second chamber to the pump inlet and the second piston displaces fluid from said third chamber to the inlet of the pump to prevent the pump inlet pressure from substantially dropping.

2. Apparatus of the character described which includes a main pump supplying fluid under pressure through first conduit means to a servomotor, pilot valve means for regulating the flow between the pump and the servomotor, second conduit means connecting the pilot valve with the inlet of the pump, the servomotor comprising of a first and second housing, first piston means defining two different effective areas with said first housing and dividing the first housing into a first chamber defined between the first housing and the larger of the two areas and a second chamber defined between the housing and the smaller of the two areas, each being adapted to receive fluid through said first conduit means as determined by the position of the pilot valve, the second housing having a second piston defining a third chamber of variable volume, means connecting said second piston to move with said first piston, the second piston having an effective area exposed to the pressure in said third chamber equal to the difference between the effective areas on the opposite sides of the first piston, the pistons being so constructed and arranged that movement of the first piston in a direction to decrease the size of the first chamber increases the size of said second and third chambers,

third conduit means connecting the third chamber with the second conduit means, whereby, when the pilot valve is positioned to supply operating fluid to the second chamber, excess fluid discharged from the first chamber and not recirculated by the pump is stored in said third chamber, and, upon movement of the pilot valve to supply fluid to the first chamber, the fluid stored in said third chamber is discharged to the inlet of the pump to prevent the pump inlet pressure from substantially decreasing.

3. A hydraulic system for actuating a control valve for supplying motive fluid to a turbine, the combination of a main pump located at the turbine and arranged to be driven thereby, a servomotor connected to actuate the control valve and comprising a first housing, first piston means defining two different effective areas with said first housing, a first chamber defined between the first housing and the larger of the two areas, a second chamber defined between the first housing and the smaller of the two areas, a second housing defining therein a third chamber between the second housing and a second piston located in said second housing, means connecting the second piston to said first piston whereby when the first piston is moved in a direction to decrease the size of the first chamber the second and third chambers are increased in size, a pilot valve controlling the flow between the pump and the servomotor, first conduit means connecting the outlet of the pump with the pilot valve, second and third conduits means connecting the pilot valve with the first and second chambers of the servomotor respectively, fourth conduit means connecting the pilot valve with the inlet of said pump, fifth conduit means connecting the third chamber with the inlet of said pump, the pilot valve containing valve means controlling fluid flow between the first, second, third, and fourth conduit means whereby, upon movement of the valve means to direct the flow of fluid from the first conduit means to the third conduit means and the second chamber, the fluid discharged from the first chamber due to the movement of the first piston flows through the second and fourth conduit means to the inlet of the pump and the fluid not recirculated by the pump flows through the fifth conduit means to the third chamber which is enlarged by the movement of the second piston where it is stored, and upon movement of the valve means in a position to interconnect the first conduit means with the second conduit means to supply fluid to the first chamber which actuates the first piston means to discharge fluid from the second chamber, the fluid discharged from the second chamber flows through the third and fourth conduit means to the inlet of the pump and the fluid stored in the third chamber is discharged therefrom by the action of the second piston means to the inlet of the pump to prevent the pump inlet pressure from substantially dropping off.

4. The hydraulic system comprising a servomotor, a pump for supplying operating fluid under pressure to the servomotor, the servomotor comprising a first housing containing therein first piston means defining two different effective areas, a first chamber defined between the first housing and the larger of the two areas, a second chamber defined between the first housing and the smaller of the two areas, a second housing defining therein a third chamber between the second housing and a second piston, means connecting the second piston to said first piston whereby when the first piston is moved in a direction to decrease the size of the first chamber the second and third chambers are increased in size, a pilot valve for controlling the flow between the pump and the servomotor, the pilot valve including a housing defining an axial bore and a pressure fluid inlet port, drain ports spaced axially on either side of the inlet port, outlet ports defined between the inlet port and each of said drain ports, and a reciprocating flow control member disposed in said bore and comprising an axially slid able member with at least two axially spaced lands disposed in said bore in coop-

eration with said outlet ports, a first conduit means connecting the outlet of the pump with said inlet port, second and third outlet means connecting said outlet ports with the first and second chambers of said servomotor respectively, fourth conduit means connecting the drain ports with the inlet of said pump, fifth conduit means connecting the third chamber with the inlet of said pump, whereby upon movement of the flow control member to a position which interconnects the first conduit means with the third conduit means that fluid will be supplied from said pump to said second chamber and the fluid discharged from said first chamber by the movement of the first piston means will be supplied to the inlet of the pump to be recirculated, the excess fluid being stored in the third chamber which increases in size upon decrease of said first chamber, and upon movement of the flow control member in the opposite direction the inlet port is connected with said second conduits means to supply fluid to said first chamber and the fluid discharged from said second chamber is supplied to the inlet of the pump and is supplemented by the fluid discharged from said third chamber due to the movement of said first and second pistons in a direction tending to decrease the size of said second and third chambers, whereby the pump inlet pressure is prevented from substantially dropping.

5. In a hydraulic servomotor system for actuating a control valve for supplying motive fluid to a turbine, the combination of a main pump located at the turbine and arranged to be driven thereby, auxiliary priming pump means for supplying fluid under pressure through first conduit means to the inlet of the main pump, a servomotor connected to actuate the turbine control valve, second conduit means for supplying fluid from the main pump to a pilot valve which regulates the flow of operating fluid to the servomotor, the pilot valve including a 35 housing defining an axial bore and a pressure fluid inlet port adapted to receive said second conduit means, the pilot valve housing also having drain ports spaced axially on either side of the inlet port, outlet ports defined be-

tween the inlet port and each of said drain ports, and a reciprocating flow control member disposed in said bore and comprising an axially slidible member with at least two axially spaced lands disposed in said bore in cooperation with said outlet ports, the servomotor comprising a first housing, first piston means defining two different effective areas with said first housing, a first chamber defined between the first housing and the larger of the two areas, a second chamber defined between the first housing and the smaller of the two areas, third and fourth conduit means connecting one of the pilot valve outlet ports with said first and second chambers respectively, and auxiliary reservoir means including a second housing containing a piston connected to move with said first piston, a third chamber defined between said second piston and the second housing, the sum of the effective areas of the pistons in the second and third chambers being substantially equal to the effective area of the first piston in the first chamber, the pistons being so constructed and arranged that when the first chamber decreases in size the second and third chambers increase, fifth conduit means connecting the pilot valve drain ports with said first conduit means, and sixth conduit means connecting the third chamber with said first conduit means, whereby, 20 upon movement of the first piston in the direction tending to discharge fluid from the first chamber, excess fluid over that recirculated by the main pump is stored in the third chamber, and upon movement of the first piston in the opposite direction the fluid stored in said 25 third chamber is discharged to the inlet side of the main pump to prevent the pump inlet pressure from substantially dropping.
